UNITED STATES PATENT OFFICE.

WILLIAM HORSMAN, OF DETROIT, MICHIGAN.

TOOL.

Application filed November 19, 1923. Serial No. 675,530.

To all whom it may concern:

Be it known that I, WILLIAM HORSMAN, a subject of the King of England, and residing at Detroit, in the county of Wayne and

5 State of Michigan, have invented a new and useful Improvement in a Tool, of which the following is a specification.

My invention relates to a new and useful improvement in a tool and particularly that 10 class of tool which is employed for removing the main or cannon pin from a watch. An object of the invention is the provision of a tool especially adapted for this use and so constructed as to provide means for engaging 15 the cannon pin of a watch firmly enough to remove it from its mounting and at the same time limited in its movement to prevent an excessive strain on the pin.

Another object of the invention is the provision of a tool of this class having a series 20 of notches formed therein for the reception of pins of various sizes and so constructed as to bring about a complete closing of the notches immediately after the engagement 25 of the pin with the tool.

Another object of the invention is the provision of a tool of this class which will be simple in structure, economical of manufacture and highly efficient in use.

30 Other objects will appear hereinafter.

The invention consists in the combination and arrangement of parts hereinafter described.

The invention will be best understood 35 from a reference to the accompanying drawings which form a part of this specification and in which,

Fig. 1 is a side elevational view of the invention,

40 Fig. 2 is an end elevational view of the invention,

Fig. 3 is a top plan view of the invention in closed position, and,

Fig. 4 is a top plan view of the invention 45 preliminary to complete closing of the same.

The invention in its preferred form comprises a pair of handles 7 and 8 which are pivotally connected together and provided with jaws 10 and 9 respectively which are 50 adapted to approach and withdraw from each other upon the opening or closing of the handles. The jaws 9 and 10 are each provided with a flattened portion 12 and 11 respectively adjacent the meeting edges thereof. Formed 55 in each of the meeting edges of the jaws are semi-circular notches, which form, when the

meeting edges are in engagement, circular openings 13. It will be noted that these openings are of various diameters to accommodate the device to the use with cannon 60 pins of different diameters.

In use the jaws are brought into engagement with the cannon pin 14 when it is in mounted position on the watch, the cannon pin resting in the notch which corresponds 65 to the sizes of the cannon pin. As the handles are pressed together the cannon pin is engaged by the edges of the notches just preliminary to the meeting of the edges of the jaws throughout their length. In this 70 way the cannon pin is securely engaged and the further pressing of the same by the jaws prevented by the meeting of the edges of the same throughout their length. The width of the jaws, which is such as to permit 75 the jaws to extend beyond the edges, on each side, of the handles a distance substantially the width of the handles themselves, permits a number of openings to be formed therein to adapt the tool for use 80 over a wide range of sizes of cannon pins. The provision of the jaws with a flattened portion adjacent the meeting edges permits the gripping of the pin close to the face of its mountings and thus assures a firm hold 85 on the same.

While I have illustrated and described the preferred form of construction, I do not wish to limit myself to the precise form of structure shown, but desire to avail myself 90 of such variations and modifications as come within the scope of the appended claim.

Having thus described my invention what I claim as new and desire to secure by Letters Patent is:

95 A tool of the class described, comprising a handle; a pair of arcuate jaws relatively movable and adapted for engaging each other at an edge, each of said jaws, on its outer surface, adjacent the meeting edge, being provided with a flat, each of said jaws 100 having a plurality of semi-circular notches formed in said edge, each notch in one of said jaws forming with a co-operating notch in the other jaw, a circular opening, the several notches in each jaw being of various sizes, said jaws extending transversely of said handles, and projecting outwardly at 105 opposite sides thereof.

In testimony whereof I have signed the 110 foregoing specification.

WILLIAM HORSMAN.
